BIRD FEEDER

John B. Olson, 814 Riverside Drive, Fort Atkinson, Wis.

Filed Sept. 15, 1960, Ser. No. 62,148

Term of patent 7 years

(Cl. D31—2)

FIG. 1 is a top perspective view showing the front and one side of a bird feeder embodying my new design;

FIG. 2 is a side elevational view thereof;

FIG. 3 is a front elevational view thereof; and

FIG. 4 is a fragmentary bottom view thereof.

The broken lines indicating a vane are for illustrative purposes only. The rear and side not illustrated are like the front and the illustrated side.

I claim:

The ornamental design for a bird feeder, as shown and described.
